UNITED STATES PATENT OFFICE.

ANTON C. MENGE, OF NEW ORLEANS, LOUISIANA, ASSIGNOR OF ONE-EIGHTH TO
GUSTAVE A. LLAMBIA, OF NEW ORLEANS, LOUISIANA.

MEANS FOR CLEANING FILTERS.

Application filed October 22, 1925. Serial No. 64,267.

This invention relates to filters and more particularly to filters employed in the treatment of sugar juices. The invention relates particularly to means for cleaning accumulations from the surfaces of the filter cells and has for its object the provision of mechanism which will operate automatically to travel over the entire surface of each cell and remove therefrom all the accumulations which tend to clog the filtering process. The invention includes means for automatically reversing the travel of the cleaning elements so that they will operate continuously to travel back and forth over the surfaces of the cells and remove all impurities. The invention also includes means whereby a stream of water will be directed upon the cells at the point where the cleaning elements engage the same and will follow the movement of the cleaning elements.

The invention is illustrated in the accompanying drawings and consists in certain novel features which will be hereinafter first fully described and then more particularly pointed out in the appended claims.

In the drawings:

Fig. 1 is a top plan view, partly broken away and partly in horizontal section, showing one embodiment of my invention;

Fig. 2 is a side elevation of the same partly broken away and partly in vertical section;

Fig. 3 is an end elevation with parts broken away and parts in section;

Fig. 4 is an enlarged section on the line 4—4 of Fig. 2;

Fig. 5 is an enlarged section on the line 5—5 of Fig. 2;

Fig. 6 is an enlarged section on the line 6—6 of Fig. 2;

Fig. 7 is a section on the line 7—7 of Fig. 2, and

Fig. 8 is an enlarged detail of the scrubbing chain.

The filter proper comprises a casing 1 which is of the usual or any approved construction and is secured to a fixed support in any desired manner. Within the casing 1 filter cells 2 are supported upon brackets 3 arranged at or near the top of the casing; and these cells extend in parallel planes transversely of the casing from end to end thereof. The filter cells consist of wire netting 70 covered with textile fabric 71 and forming a hollow box or

chamber, as will be understood upon reference to Fig. 6. Rods 72 pass through the top bights or folds of the netting and have their ends seated in the brackets 3 to suspend the cells. The bottom of the casing 1 is tapered toward its center from its ends and its sides, as indicated at 4, and at the center of the casing a T-coupling 5 is connected to the bottom thereof through an inlet pipe 6. Short lateral pipes 7 connect the T 5 with the parallel pipes 8 and 80, cut-off valves 81 and 82 being provided in the pipe 8 at opposite sides of the pipes 7 while the pipe 80 likewise is provided with similar valves 83 and 84. At one side, the pipe 8 is connected to the source of sugar juice supply and the pipe 80 is connected with a reserve tank, the flow being controlled by the valves 81 and 83, respectively. At the opposite side, the pipe 8 is connected with a water supply and the pipe 80 leads to a waste discharge, the flow being controlled by the valves 82 and 84, respectively. A manifold 9 extends longitudinally of the casing below the same, and this manifold 80 is connected with the several cells by pipes 10, each of which is equipped with a cut-off valve 11, a pipe 12 leading from one end of the manifold to an air pump or other vacuum-creating mechanism (not shown). The pipe 12 is equipped with a cut-off valve 12' which is normally closed.

I secure in each upper corner of the casing a bracket 13 which provides a bearing for the upper ends of shafts 14 and 15, the lower ends of said shafts being rotatably fitted in packing boxes 16, secured upon the bottom of the casing, and the shaft 14 between its ends constituting a threaded rod or fine worm, as shown at 17, while the shaft 15 between its ends carries a coarse worm 18. In Fig. 4 I have shown an arrangement whereby the shafts 14 and 15 are so supported that grit cannot have access to the bearings. Long bolts 73 depend from the bottom of the casing through the flanges of the box 16, and nuts 74 on the bolts hold the box against the bottom of the casing. Lower nuts 75, mounted on the bolts below the gland 76, hold the gland in close engagement with the box. Below the gland, spaced collars 77 are secured upon the shaft and a supporting plate 78 is engaged between these collars and around the shaft, the ends of the plate being secured upon the 110

bolts 73 by nuts 79. Upon the meeting walls of the casing are vertical guide ribs 19 which engage grooves formed in the sides and ends of slidable journal boxes 20 which are fitted upon the worms or threaded shafts 17 and are thereby adapted to travel vertically, being guided in their vertical movements by the said ribs 19, as will be understood. Upon each end of the box 20 is 10 pivotally mounted a cleaner arm 85 which is pressed into engagement with the worm 17 by a spring 86 and is equipped at its free end with a brush or scraper 87 fitting to and riding in the thread of the worm so as 15 to remove grit therefrom. Extending from end to end of the casing at each side thereof is a brush shaft 21 which has its ends journaled in the adjacent boxes 20 and is equipped near each end with a worm gear 22 meshing with the adjacent coarse worm 18 so as to be rotated thereby. Disposed upon each shaft 21, between the vertical planes of the several filter cells 2, are sprockets 23 about which are trained brush chains 24. The alternate links of the chains 24 carry lateral brushes 25 which bear at their ends against the surfaces of the respective cells so that when the shafts 21 are rotated these brushes will be caused to travel transversely of the casing and scrape therefrom 30 the accumulated matters which tend to clog the filtering operation. It will be understood that the shafts 14 and 15 are simultaneously rotated and the engagement of the worms 18 with the worm gears 22 rotate the shafts 21 while the rotation of the finer worms or threaded shafts 17 will effect vertical travel of the journal boxes 20 and thereby cause the said shafts 21 to travel vertically 35 within the casing while they are rotating, the brushes being thereby caused to travel vertically as well as transversely over the surfaces of the cells and treat the entire area thereof. The brush-carrying links are 40 also equipped with cutting or scraping knives 88 which cut through or break up the accumulation or cake of matter between the cells before the brushes reach it so as to provide a path or clearance which will permit the brushes to operate efficiently on the 45 sides of the cells.

To the lower ends of the shafts 14 and 15 are secured gear wheels 26 and 27 which are intermesh so that the said shafts will be 50 rotated simultaneously, and the lower end of the shaft 14 is extended below the gear 26 thereon and equipped with a beveled gear 28 meshing with a beveled gear 29 secured upon the driving shaft 30 which is mounted in 55 suitable brackets 131 secured upon the end walls of the casing, the several shafts and gears thus far described being duplicated at the two ends of the casing, as shown and as 60 will be understood, with the exception that the driving shaft 30 is extended beyond one

end of the casing to receive the actuating mechanism while the corresponding shaft 31 at the opposite side of the casing is not connected directly with the actuating mechanism but is connected indirectly therewith through the medium of gearing about to be described. Upon each shaft 30 and 31 at the driving end of the apparatus, I secure a beveled gear 32 which meshes respectively with similar gears 33 upon the opposite ends 75 of a worm or threaded shaft 34 which is mounted in bearings 35 secured upon the adjacent end of the casing, a guide rod 36 being also secured to and extending between said bearing brackets. A slide 37 is provided 80 with an internally threaded bore engaging the threaded shaft 34 and is also engaged with the guide rod 36 so that it may slide along the same. The shaft 30 is equipped with opposed loose pulleys 38 and 39 and clutch members 40 and 41 are fitted upon the said shaft adjacent the respective pulleys so that one or the other of the pulleys may be locked to the shaft and impart rotation thereto. These clutch members are connected 85 to a collar 42 which is slidably mounted upon the shaft 30 between the clutch members and is engaged by one end of a lever 43 fulcrumed between its ends and connected by a link 44 with one end of a shifting rod 45. This shifting rod or bar 45 is provided with laterally extending arms or forks 46 and 47 which pass around or partly around the threaded shaft 34 and are disposed at 90 opposite sides of the slide 37 so that, when the said slide reaches either end of its movement, it will impinge against one of said arms and thereby shift the bar or rod 45 so that the lever 43 will be rocked and the active clutch member 40 or 41 released and the other clutch member thrown in so that the direction of rotation of the shaft 30 will be reversed. Buffer springs 89 are provided around the shaft 34 at the forks 46 and 47 to cushion the impact of the slide. A supporting link 48 is pivoted at one end upon the end of the casing 1 and at its opposite end to the end of the bar 45 and the link 44, as shown clearly in Fig. 1, so that the said bar will be held against dropping and will 105 be maintained in operative relation to the threaded reversing shaft 34. Near the opposite end of the bar 45 a second supporting link 49 is provided. Belts 50 and 51 are trained about the loose pulleys 38 and 39, respectively, and one of said belts is crossed. The said belts also pass around loose pulleys 52 and 53 upon a power shaft 54 and clutch elements 55 are arranged between the said 110 pulleys and are adapted to lock them to the power shaft, as will be understood. Crossed levers 56 are connected with the respective clutch members 55 and the outer ends of these levers are connected by toggle links 57 and a coupling link 58 with a hand lever 59. 115

120

125

130

135

If the lever 59 be rocked so as to pull upon the outer ends of the levers 56, the clutch elements 55 will be moved from the pulleys 52 and 53 and the said pulleys will come to rest but if the lever 59 be rocked in the opposite direction the clutch members will be thrown in so that the pulleys will rotate with the power shaft and will transmit motion to the corresponding pulleys 38 and 39. The shaft 30, however, will not be actuated unless one or the other of the clutches 40, 41 be thrown in and the direction of rotation of the shaft 30 will, of course, be determined by the clutch which is thrown in. Assuming that the shaft 30 is rotating in one direction, the worms 17 and 18 will be rotated as previously described and the shifting worm shaft or threaded bar 34 will also be rotated through the medium of the gears 32 and 33. The rotation of the shaft 34 will, of course, cause the slide or crosshead 37 to move along the guide rod 36 which holds it to a rectilinear path and eventually the slide will impinge against the arm 46 or the arm 47 and impart a slight endwise movement to the shifting bar 45 which will result in rocking the lever 43 to one or the other side and, consequently, throw out the active clutch 40 or 41 and throw in the inactive clutch, thereby reversing the direction of rotation of the shaft 30. When the shaft 30 is reversed, of course, the direction of travel or rotation of all the working parts will be likewise reversed and the action is so timed that the reversal will occur when the brushes have reached either the tops or the bottoms of the filter cells.

Extending longitudinally of the casing at the bottom of the same and near one side thereof is a wash-out pipe 60 which is rotatably supported in the end walls of the casing 1. One end of this wash-out pipe is closed and has secured thereto a lever or crank 61 which is connected by a link 62 with the crosshead or slide 37. It will thus be seen that as the said slide travels back and forth the pipe 60 will be rocked or oscillated and the stream of water or steam escaping therefrom will be consequently so directed that it will play directly upon the brush chains and will follow the movements thereof. The opposite end of this wash-out pipe is swiveled in a box 62 secured upon the opposite end of the filter casing and supplied with water through a pipe 63 and with steam through a pipe 64 equipped respectively with cut-off valves 65 and 66.

The end of the manifold pipe 9 remote from the vacuum pipe 12 leads to a point of deposit for the filtered juices. Each pipe 10 extends up into a filter and is provided, within the cell, with openings 90 through which the filtered juice may escape from the cell. The pipe 10 serves to maintain the shape of the cell at one end thereof while

a branch pipe 91 extends along the bottom bight of the cell and is formed with openings 92 to facilitate the escape of the filtered juice.

When the filter is in operation, the valve 81 and the valves 11 are open and all other valves are closed, the syrup to be filtered flowing under pressure past the valve 81 and through the coupling 5 into the casing 1. It then rises to and flows through the fabric 75 of the filter cells whereby the impurities are removed, the filtered juice escaping through the pipes 10 and 91 and thence to and through the manifold discharge pipe 9.

When the filter is clogged, so that cleaning is necessary, the valve 81 is closed and the valve 83 is opened to permit the unfiltered syrup to flow to the reserve tank. Then the valve 83 is closed and the valves 82 and 84 are opened; the outlet valve of the manifold 9 is closed and the valve 12 is opened, a vacuum being established through the last-mentioned valve to hold the cakes to the filter cells while water is admitted through the valve 82 to wash out the juices held in the waste matter. After the juices have been thus driven off, the valve 82 is closed, and the valve 65 or 66 (or both) is opened and the gearing then set in motion to operate the scrubbing chains and the wash-out pipe 95 60 in the before-described manner.

Having thus described the invention, I claim:

1. Means for cleaning filters comprising a brush element, means for causing said brush element to travel over the filtering surface from side to side and from top to bottom thereof, and means operating in unison with the movement of the brush element for directing a stream of fluid upon the filtering surface at the point of contact of the brush element therewith.

2. Means for cleaning filters comprising a plurality of brush elements disposed between and in contact with the opposed surfaces of adjacent filtering elements, means for causing the brushes to travel from top to bottom and from side to side of the filtering elements, and means operating in unison with the movement of the brushes for directing streams of fluid against the filtering elements at the points of contact of the brushes therewith and causing said streams to follow the movements of the brushes.

3. Means for cleaning filters comprising endless chains of brushes disposed between and in contact with the opposed surfaces of adjacent filter cells, means for causing the chains of brushes to travel across the surfaces of the filter cells, means for causing the chains of brushes to travel vertically of the filter cells, and means for directing streams of fluid against the surfaces of the filter cells at the points of contact of the brushes therewith.

4. Means for cleaning filters comprising a plurality of chains of brushes disposed between the opposed surfaces of adjacent cells with the brushes in contact with said surfaces, means for effecting travel of the chains in the direction of their length, and means for effecting vertical bodily travel of the chains.
5. Means for cleaning filter cells comprising endless chains of brushes disposed between the cells and in contact with the surfaces thereof, vertically disposed worms arranged adjacent the series of cells, means for rotating the said worms, said worms being arranged in pairs and each pair comprising a finer and a coarser worm, journal boxes slidably supported adjacent and engaging the several finer worms, shafts mounted in said boxes and extending past the series of filter cells and operatively engaged with the several chains of brushes, and worm gears on the several shafts meshing with the coarser worms.
6. Means for cleaning filter cells comprising endless chains of brushes disposed between and in contact with the surfaces of the filter cells, means for causing the brushes to

travel back and forth across the surfaces of the cell from side to side and from top to bottom thereof, a wash-out pipe rotatably mounted below the cells, and means for rocking said pipe simultaneously with the travel of the brushes.

7. Means for cleaning filter cells comprising a rotatably mounted shaft, a plurality of brushes disposed between the filter cells and operatively connected with said shaft whereby to be driven therefrom, a reversing shaft geared to the first-mentioned shaft, a shifting bar arranged adjacent said reversing shaft and having lateral arms extending over the same, constantly driven loose pulleys upon the first-mentioned shaft, clutch members adapted to alternately lock said pulleys to the shaft, connections between said clutch members and the shifting bar, and a slide engaged with the reversing shaft and caused to travel along the same to impinge against the lateral arms of the shifting bar whereby to shift the said clutch members and reverse the direction of rotation of the first-mentioned shaft.

In testimony whereof I affix my signature.
ANTON C. MENGE. [L. S.]
